UNITED STATES PATENT OFFICE.

ISAAC H. LEVIN, OF NEWARK, NEW JERSEY.

ELECTROLYTIC GAS-GENERATOR.

1,219,966.

Specification of Letters Patent. Patented Mar. 20, 1917.

Application filed November 18, 1916. Serial No. 112,211.

To all whom it may concern:

Be it known that I, ISAAC H. LEVIN, a citizen of the United States, and a resident of Newark, in the county of Essex and State 5 of New Jersey, have invented certain new and useful Improvements in Electrolytic Gas-Generators, of which the following is a specification.

My invention relates to electrolytic apparatus designed to produce hydrogen and oxygen gases by subjecting water containing a small quantity of a suitable electrolyte such, for example, as potassium hydroxid, sulfuric acid, etc., to the action of a current 10 of electricity which is caused to flow therethrough from one electrode to another, both of which are submerged in the water; the electrolyte being dissociated by the water, oxygen being liberated at the positive electrode or anode, and hydrogen at the negative electrode or cathode, all in accordance with the well known phenomenon commonly referred to as the decomposition of water by an electric current.

25 My invention relates particularly to that type or class of electrolytic cells, or electrolytic gas generators, in which the liquid acted upon is contained in a suitable receptacle or casing, and in which the electrodes 30 are entirely independent of the receptacle or casing, as distinguished from electrolytic gas generators in which the casing or container forms one of the electrodes.

The objects of my invention are to provide 35 an improved electrolytic gas generator of the kind or type above referred to and in which the interior of the casing is divided into three compartments, within each of which an electrode is located; to provide an 40 improved electrolytic gas generator in which the casing is made up of two dished end casting members or sections in connection with one or more intermediate annular or ring-like members or sections, so that casings for 45 generators of any required capacity may be formed by assembling the requisite number of intermediate ring sections with two dished end sections; to provide improved 50 means for supplying water to the interior of the generator casing to replenish the loss due to the decomposition thereof; to provide improvements in and relating to various of the elements and parts of devices of

the type above referred to; and to otherwise improve upon and enhance the efficiency of electrolytic gas generating devices 55 of the kind to which my invention relates.

With the above enumerated and other objects of invention in view, my invention consists in the improved electrolytic gas generator and parts thereof illustrated in the accompanying drawings, described in the following specification, and particularly claimed in the concluding claims, and in such variations and modifications thereof as 60 will be obvious to those skilled in the art to which my invention relates.

In the drawings accompanying and forming a part of this application, and wherein the preferred embodiment of my invention 70 is illustrated:

Figure 1 is a view showing a section of my improved electrolytic gas generator upon a plurality of vertical planes indicated by the broken line 1, 1, Fig. 3;

Fig. 2 is a view showing my invention in plan;

Fig. 3 is a view showing a section taken upon a horizontal plane indicated by the line 3, 3, Fig. 1, looking down;

Fig. 4 is a view showing a section upon vertical planes at right angles to the planes of Fig. 1; and indicated by the broken line 4, 4, upon said figure, looking toward the right;

Fig. 5 is a view similar to Fig. 4, but showing a modified form of my invention;

Fig. 6 is a view upon a smaller scale showing a frame member employed in my device;

Fig. 7 is a view showing a pocket member used in my device in perspective;

Fig. 8 is a sectional view showing the construction of certain packing members employed in my device;

Fig. 9 is a view showing one of two filling devices with which I have shown my improved generator as equipped, this view being upon a transverse vertical plane indicated by the line 9, 9, Figs. 2 and 3;

Fig. 10 is a fragmentary view showing certain pressure and water level equalizing means employed in my device, in perspective; and

Fig. 11 is a view showing a second filling 105 device provided for my generator, the same

also performing certain gas washing and safety functions, this view being taken upon a transverse vertical plane indicated by the line 11, 11, Fig. 2, although certain elements are displaced somewhat and others beyond said plane are shown in section, in order to better explain the device.

Referring to the drawings, the reference numerals, 11, 12, designate two end sections of a three-part closed external casing within which the electrodes, diaphragms, and other elements to be hereinafter more particularly described, of my improved electrolytic gas generator, are located, while 13 designates an intermediate section held in place between said end sections; the three sections referred to forming a fluid tight casing or receptacle adapted to contain the water to be decomposed, and having internal electrode compartments, and gas tight chambers located at its upper end within which the gases produced collect, all as hereinafter explained. The end section members are formed from comparatively thin plate or sheet metal, and are herein referred to as dished because they are of dish or pan-like form of large area and of comparatively slight depth, such, for example, as are disclosed and claimed in my application for patent for electrolytic gas generators, filed upon December 20, 1915, Serial Number 67,834; while the intermediate section member is in the form of a short piece of a tube of large diameter, which member I refer to as of annular or ring-like form because it resembles a ring and because the casing as a whole may obviously be of a form more or less approaching a true circular form, as seen in side elevation, instead of rectangular in form as illustrated in the drawings.

The free edges or ends of the several casing members are provided with flanges as shown at 14, Figs. 2 and 11, in order to provide a more extensive area of contact between the ends of adjacent casing members and the peripheries of two frame members held in place between them; the flanges of the casing members and the peripheries of the frame members being secured together along their meeting edges by welding, soldering, brazing, riveting or otherwise, in order to form a unitary casing structure within which the electrodes and other elements of my device are located and held in fixed positions throughout the life of the generator, the same as in my pending application for patent hereinbefore referred to.

Fig. 6 shows one of the frame members above referred to by itself, the two being alike in all respects and corresponding parts of them being designated by reference numerals without and with primes in the various figures of the drawings. These frame members are made from plate or thick sheet

metal, and have upper portions 18, 18' which provide or form partitions which divide the upper portion of the interior of the casing into three gas compartments or chambers, within the two outer of which, designated by the reference numerals 15, 16, Figs. 4 and 11, oxygen accumulates when the generator is in operation, while hydrogen accumulates within the middle compartment or gas chamber 17. Each frame member also includes oppositely located downwardly extending side portions 19, 19'; and a bottom bar or strip 20, 20' connecting the lower ends of the sides together, the latter of which is provided with a plurality of spaced upwardly extending lugs 21, 21' as best shown in Figs. 1 and 6.

The reference numerals 22, 22', designate two diaphragms made of porous material such, for example, as asbestos, which diaphragms are secured to and carried one by each of said frame members. These diaphragms divide the lower portion of the interior of the casing into three electrode compartments or chambers; the outer compartments 23, 24, being anode compartments and the middle compartment 25 being a cathode compartment in the embodiment of my invention illustrated in the drawings.

The diaphragms are shown as held in place upon the frames by means of strips 26, 26', extending along the tops, down the sides, and across the bottom of the diaphragms, and secured to the frame members by means of rivets; the bottom strips being secured to the upper ends of the lugs 21, 21', see Fig. 1, whereby openings 27, 27' are provided beneath the lower edges of the diaphragms through which the lower ends of the electrode compartments 23, 24, and 25 are placed in constant communication with one another.

Located within the anode compartments 23, 24, are two anodes, 28, 29, which are shown as in the form of thin metallic plates provided with perforations to permit a better circulation of the water being decomposed, and a more free discharge of the oxygen liberated at their surfaces. These anodes may be of any suitable material, and they are both connected with the positive lead or terminal of the dynamo employed to furnish current for decomposing the water contained in the casing, as will be understood.

Secured to the lower corners of the anodes are supports 30, 30', having each a hole at its outer end, and 31, 31' designate pockets formed preferably of metal and secured in place within and at the lower end of, and at the outer corners of the casing; each of which pockets include two side walls spaced apart from one another and having a hole, the holes being arranged in line with one an-

other as best shown in Fig. 7. The reference numerals 32, 32', designate pins of non-conducting material which extend through the holes provided in the sides of the 5 pockets, and also through the holes at the ends of the supports 30, 30', while 33, 33' designate insulating material, such, for example, as asbestos, arranged within the pockets and about the ends of the supports 10 and the purpose of which is to insulate the said supports from the metallic pockets and from the wall of the casing.

The construction above described provides anchoring means whereby the lower 15 corners of the anodes are held in fixed positions, and their lower ends prevented from coming into contact with the wall of the external casing, or with the diaphragms, which is a feature of importance in electrolytic gas 20 generators having anodes of large area located within electrode compartments of slight thickness; and the use of a porous material pervious to the liquid within the casing such as asbestos, asbestos combined 25 with rubber, or an equivalent insulating material, provides effective and convenient insulation for use in generators of the type to which my invention relates.

The metallic pockets or equivalent members to which the supports 30 are anchored 30 may be secured in place within the casing in any way, as by welding or riveting the same to the wall of the casing; and may be made with separate side walls and an intervening end wall, as shown in Fig. 7, or 35 in a single piece from a suitable blank by suitable pressing operations, by casting operations, or otherwise, as will be appreciated.

40 The upper ends of the anodes are provided with conducting bars or terminals 34, 35, which extend through openings provided in the top wall of the casing, and are of sufficient stiffness to support the upper ends of 45 the anodes in fixed positions so that they cannot come into contact with the wall of the casing, or with the diaphragm, the same as in the case of the lower ends of the anodes.

50 Suitable packing members are provided between the top wall of the casing and the conducting bars in order to prevent the escape of gas from the gas chambers through which they pass; each packing being shown 55 as comprising an expansible member 36 of soft rubber or similar insulating material surrounding the bar and filling the opening through which it extends, insulating plates 37, 38, located above and below said expansible member and provided with openings 60 to accommodate the conducting bar, and metallic plates 39, 40, also having openings, located above and below said plates, and having holes through which bolts 41 extend,

which, upon being shortened, draw the 65 plates 39, 40, toward one another and against the expansible member; thus compressing said member and forcing the periphery thereof into contact with the edge or wall of the opening in which it is located and securing 70 a tight joint about the conducting bar and opening. The lower one of the insulating plates 38 is formed in two parts, see Fig. 8, in order that the same may be put in place from the exterior of the casing 75 through the opening in the top wall thereof, or removed in a similar way; the width of said plate being approximately the same as the opening in the casing, and the slots 42 at the ends of the halves permitting the ends 80 to move sidewise past and into and out of operative relation with the bolts, as the parts which form the lower plate are put in place or removed.

The reference numeral 43 designates the 85 cathode of my gas generating device, the same having vertically extending corrugations upon each side, as shown in Figs. 1 and 3, in order to provide a better circulation of the liquid within the central electrode compartment 25 in which it is located and a more free discharge of the hydrogen liberated at the surfaces thereof; and the same may be made from any suitable material and have any structural features 90 so long as its size and shape are such that it will be contained within the electrode compartment provided to receive it. This cathode is provided with supports at its two lower corners, one only of which is 95 shown at 44, Fig. 4, which supports are anchored within and insulated from suitable pockets in the same way as the supports 30, 30', for the anodes, the purpose of said supports being to anchor the lower end of the 100 cathode within the casing and hold it centrally within the chamber or compartment in which it is located. The upper end of the cathode is provided with a conducting bar or terminal 45 which holds the upper end in 105 proper position, the same as in the case of the anodes, which bar extends through a packing member of the same form and construction as the packing members provided for the conducting bars extending from the 110 anodes.

In the form of my invention illustrated in Figs. 1 to 4 inclusive the casing of the generator is made up of two dished end casing members or sections, together with a single 120 intermediate annular or ring section, as explained, and the interior of the casing is divided into three compartments, two for the anodes and one for the cathode of the generator. In the form illustrated in Fig. 5, 125 however, a plurality of intermediate ring sections 13 similar to the casing members or sections 13 in Figs. 1 to 4 are employed, the

said intermediate sections being assembled with two dished end sections 11' and 12' like the end sections 11, 12, hereinbefore described. Frame members like the frame members already described are arranged in alternation with and held in place between the ends of adjacent sections of the casing, which frame members carry diaphragms 46, which divide the interior of the casing into a plurality of electrode compartments; but the scheme of connecting two anodes in parallel, and using a single cathode between them, is not made use of, the internal compartments being alternately anode and cathode compartments within which anodes 47 and cathodes 48 are located.

In this form the anodes 47 and the cathodes 48 are supported and anchored within the casing at their lower ends, the same as hereinbefore explained, and are provided with conducting bars 49, 50, extending through packing members in the top wall of the casing; although the showing as to these minor features is more or less conventional in this figure.

It will be appreciated that the construction illustrated in Fig. 5 provides an arrangement in which and shows how two dished end section members may be assembled with a greater or less number of intermediate ring sections, all of said sections being secured together as hereinbefore explained, to thereby provide a casing for a generator of any required size, whereby generators of widely different sizes or capacities may be assembled and made up from dished end and intermediate ring sections all of one form and size.

The openings 27, 27' beneath the diaphragms place the three electrode compartments or chambers in permanent communication with one another at their lower ends, as will be understood. It is, however, desirable to place these compartments in communication at their upper as well as at their lower ends, to which end I provide two trough or channel shaped members 51, 52, which are secured in place upon opposite sides of the frame members adjacent the level of liquid in the several compartments. These members are provided with openings 53, 54, and they preferably extend above the level of the liquid in the compartments and are open at their upper ends; and the frame members are provided with openings 55 located within and so as to be covered by the channels, and some little distance below the openings 53, 54, as shown.

All these openings lie below the level of the water in the several compartments when the generator is in use, so that gas cannot flow from one of the gas chambers provided by the partitions 18 at the upper end of the casing into the other; as the lower edge of the partition portion of the frame mem-

ber lies below the normal level of liquid in the casing as best shown in Fig. 1 of the drawings. The upper ends of the compartments are, however, placed in communication with one another through the equalizing means here described and, should the level of water become higher in one compartment than in the one next to it, a flow will occur from one side of the partition between said compartments through the passage provided by the openings 53, 54, 55, and the interior of the channel members in one direction or the other, thus equalizing the level of liquid within adjacent electrode compartments, and upon opposite sides of the partition between them.

Each of the frame members with which the generator is provided should obviously be equipped with one or more equalizing devices such as are above described in order to maintain a constant level of water throughout the casing, and equal pressures within the several gas chambers at the upper end thereof. Also, while the equalizing device in question is shown as used in connection with other equalizing means such as is provided by the openings 27, 27', this is not necessarily the case; and the equalizing devices located adjacent the level of liquid in the casing as above described may form the sole means for securing a constant level within the casing, and equal pressures within the several gas chambers.

I have shown my improved electrolytic gas generator illustrated in Figs. 1 to 4 as equipped with two means whereby water may be supplied to the interior of the generator casing, both of which perform functions, differing in the two cases, in addition to the function of supplying water to the casing to compensate for the water decomposed when the generator is in use. Any particular gas generator may, however, obviously be equipped with one only of these water supplying or filling devices, or with both of them, as herein disclosed.

The less comprehensive of the two filling means above referred to is shown in its relation to the casing in Figs. 1 and 2, while Fig. 9 is another view of the same and shows the relation of its several parts to the electrode compartments within the casing.

This filling means is shown as comprising a trough or receptacle 56, from which two conduits 57, 58, lead into the outside or anode compartments of the generator, while a third conduit 59 leads into the central cathode compartment; the inlet ends of which conduits communicate and lead from the receptacle at different levels. The lower end of each conduit is provided with a slotted cap 60 closed at its bottom so that gas, which is more or less distributed throughout the entire mass of liquid in the

electrode compartments in the form of bubbles, cannot rise directly into the conduits and escape to the atmosphere; but which caps permit the flow of water through their slots and into the electrode compartments. The central conduit 59 in the embodiment of my invention illustrated, extends up through the bottom of the receptacle for a less distance than the side conduits 57, 58; from which it follows that whenever water is poured into the trough or receptacle it will run into the central cathode compartment for a short time after the level has fallen below the inlet ends of the conduits which lead into the anode compartments and water has ceased to flow into said compartments.

The water within the generator casing contains a small quantity of a suitable electrolyte such as potassium hydroxid, sulfuric acid, etc., as explained, and it is found that when the generator is in operation the electrolyte tends to pass into the cathode compartment; so that the water within said compartment will, after the generator has been in operation for some time, be found to contain an appreciably greater percentage of the electrolyte than the water in the anode compartments. My filling device above explained, however, prevents this concentration in the cathode compartment, for it will be obvious that each time that water is supplied to the casing a little more will enter the cathode compartment than enters the anode compartments, thus carrying small quantities of the electrolyte out of the cathode compartment and into the anode compartments each time water is supplied to the casing; for it will be remembered that the several electrode compartments are in constant communication with one another through one or both the equalizing means above referred to and described, so that the level of the liquid is equalized after each filling operation and is the same in all the chambers when the generator is in operation; assuming of course that the pressure of the gases is the same in the several gas chambers which is a condition intended to be attained and which substantially exists when the generator is in use, although it will be appreciated that slight fluctuations of pressure and liquid level may occur in the practical operation of the device.

The second of the filling devices above referred to is best shown in Fig. 11 and this device, in addition to providing for the supply of water to the interior of the generator casing provides means for washing the gases produced in substantially the same way that the gases are washed in the wash bottles or lanterns at present in use with electrolytic gas generating devices; and provides, in addition, a safety device whereby, should the pressure be reduced below atmospheric pres-

sure in either of the conduits through which the gases produced flow, air from the surrounding atmosphere, instead of gas from the other conduit, will enter the conduit in which the reduction of pressure occurs.

In this last mentioned form of filling device two water chambers 61, 61' are interposed in the conduits through which the gases produced pass to the gas holders commonly provided for storing the gases, said chambers being preferably formed by sections of glass tubing 62, 62', held in place between lower and upper heads 63, 64, 63', 64', so that the bubbles of gas passing through the water in said chambers will indicate whether or not the generator is operating properly, the same as in the lanterns or wash bottles ordinarily used with gas generating devices of the type to which my invention relates. Connected with the lower head 63 is a bifurcated pipe 65, the branches of which lead into the anode chambers 15, 16; while an outlet conduit 66 leads from the upper head 64 and through which oxygen is conducted from the generator. In like manner the lower head 63' is connected with a pipe 67 which extends from the cathode compartment 17; while an outlet conduit 68 leads from the upper head 64' and conducts hydrogen from the generator.

Water is supplied to both said water chambers from a common supply trough or receptacle 69 having water supply conduits 70, 70' leading, respectively, to the lower heads 63, 63' of the water supply device; the upper ends of the said conduits extending above the level of water in the water chambers a distance greater than the head of water due to the pressures within the outlet conduits and gas reservoirs, in order that the columns of water within the conduits will not be forced or blown out of said conduits by the pressure of the gases within the gas outlet conduits.

The lower heads 63, 63' are provided each with a threaded opening within which the lower ends of two gas discharge pipes 71, 71' are secured, which pipes are provided with outlet openings adjacent their upper ends and with open bottom petticoats or bells 72, 72', which are submerged in the water within the water chambers; whereby gas outlet passages are provided through which the gases produced flow from the electrode compartments. The gases, in flowing from the gas chambers, pass beneath the lower edges of the bells and upward in the form of bubbles through the water in said water chambers, during which they obviously overcome or flow against a pressure due to the head of water in the water chambers and indicated by the distance H, Fig. 11, and indicate whether or not gas is being produced properly by the generator.

Located within the gas discharge pipes

above referred to are water supply pipes 73, 73', having each a water seal secured by return bends 74, 74' at their lower ends, in order to divert the flow of the gases through the water in the water chambers and to prevent a direct flow through said water supply pipes. The upper ends of the water supply pipes, the gas discharge pipes, and the bells will be secured together by welding, 10 soldering or otherwise, so as to provide tight joints between them, as will be appreciated.

In view of the premises it will be appreciated that when water is poured into the supply receptacle 69 it will flow therefrom through the water supply conduits 70, 70' and into the water chambers 61, 61'; over the upper ends of the bells 72, 72' and water supply pipes 73, 73'; and down through said water supply pipes and the traps 74, 74' at their lower ends and into the electrode compartments within the casing. Water is thus supplied to both the anode and cathode compartments; and, while in the construction illustrated the water would for the most 20 part enter the left hand anode compartment, the flow may be divided so as to enter both anode compartments. In any event the liquid level is equalized within the casing, as above explained, so that a constant level exists 25 therein irrespective of the quantities actually supplied to the several electrode compartments.

In electrolytic gas generating devices of the kind to which my invention relates the 30 gases which pass from the electrode compartments carry considerable water suspended in them, because of the agitation and mixing action which occurs at the surface of the liquid as the rising bubbles break through the surface layer and enter the gas 40 chambers, together with a proportionate quantity of the electrolyte which is dissolved in the water; from which it results that the water in the washing bottles of electrolytic 45 gas generators at present in use becomes more and more concentrated as the generator is used until the water has dissolved all the electrolyte which it can dissolve, after which the electrolyte passes on with the gas 50 and becomes an impurity thereof. In my device as above explained, however, the water or solution within the water chambers is washed back through the water supply passage provided by the pipes 73, 73', and into 55 the electrode compartments each time that water is supplied to the generator, so that the electrolyte is continually restored to the water in said compartments and the quantity of electrolyte in the water used for 60 washing the gases is kept at a minimum.

In view of the fact that the water supply conduits 70, 70' extend above the level of water in the water chambers 61, 61', as above explained, it will be obvious that water will 65 stand in said conduits a distance H' above

the level of the water in the water chambers, which distance will be equal to the head H in the water chambers and will be dependent upon the pressure of the gases within the gas outlet conduits and gas reservoirs or 70 holders; and that the gases cannot flow out through said water supply conduits because they extend above the height at which the water stands in them when equilibrium exists throughout the system, the columns of 75 water in them being of sufficient height to prevent outflow from the water chambers through said conduits. If, on the other hand, the pressure is reduced below atmospheric pressure in one or the other of the 80 gas outlet conduits or gas holders, due, for example, to an insufficient supply to a pump connected with the conduits or reservoirs and employed to compress the gases, which is a condition commonly present in gas 85 manufacturing plants, then the water will be withdrawn from the water supply pipe 70, or 70' associated with the gas outlet conduit in which the reduction of pressure occurs; and air from the external atmosphere, 90 as distinguished from gas from the other gas outlet conduit, will flow through the supply pipe affected and into the system to supply the reduction of pressure. Thus, where pumps are used to compress the gases, as is 95 commonly the case in gas manufacturing plants, a pump associated with one gas outlet conduit or reservoir can under no circumstances draw gas from the other outlet conduit, or from gas chamber or reservoir into 100 which said other conduit discharges.

Having thus described and explained my invention, I claim and desire to secure by Letters Patent:—

1. An electrolytic gas generator having an 105 electrolyte chamber and a gas outlet, and means whereby liquid can be supplied to the electrolyte chamber through the gas outlet.

2. In an electrolytic gas generator having 110 an internal liquid containing compartment, and a gas outlet leading therefrom; a liquid sealing device included in said gas outlet; and means whereby liquid may be supplied to said liquid containing compartment 115 through said liquid sealing device.

3. In an electrolytic gas generator having an internal liquid containing compartment, and a gas outlet conduit leading therefrom; a liquid sealing device included in said gas 120 outlet conduit; means whereby liquid may be supplied to said liquid sealing device; and a liquid supply conduit leading from said liquid sealing device and discharging into said internal compartment, and through 125 which liquid may be supplied to said compartment.

4. In an electrolytic gas generator having an internal compartment adapted to contain a liquid, and a gas chamber above said com- 130

- partment; a water chamber located above said compartment; a gas outlet passage leading from said gas chamber into, and the upper end of which is sealed by, the water in 5 said water chamber; a gas outlet conduit leading from said water chamber; means for supplying water to said water chamber; and means for conducting water from said water chamber into said electrode compartment.
- 10 5. In an electrolytic gas generator having an electrode compartment within which a gas is produced; a water chamber located above said compartment; a gas outlet passage through which the gas produced in said 15 electrode compartment passes, and the discharge end of which is sealed by the water in said water chamber; a gas outlet conduit leading from said water chamber; a water supply conduit leading into, and through 20 which water is supplied to said water chamber; and a water supply passage leading from said water chamber and through which water is supplied to said electrode compartment.
- 25 6. In an electrolytic gas generator having an electrode compartment within which a gas is produced; a water chamber located above said compartment; a gas outlet passage through which the gas produced in 30 said electrode compartment passes, and the discharge end of which is sealed by the water in said water chamber; a gas outlet conduit leading from said water chamber; means for supplying water to said water 35 chamber; and a water supply passage leading from said water chamber and through which water is supplied to said electrode compartment.
- 40 7. In an electrolytic gas generator having an electrode compartment within which a gas is produced; a water chamber located above said compartment; a gas outlet passage through which the gas produced in said 45 electrode compartment passes, and the discharge end of which extends into, and is sealed by the water in said water chamber; a water supply passage leading from said water chamber and discharging into said electrode compartment, and having a water seal 50 for preventing the flow of gas therethrough; a gas outlet conduit leading from said water chamber; and a water supply conduit leading into, and through which water is supplied to said water chamber.
- 55 8. In an electrolytic gas generator, a casting having an electrode compartment, and a gas chamber above said compartment; a water chamber located above said compartment; a gas outlet passage leading from 60 said gas chamber into, and having a water seal within said water chamber; a water supply pipe leading from said water chamber and through which water is supplied to said electrode compartment, and having a water seal for preventing the flow of gas 65
- therethrough; a gas outlet conduit leading from water chamber; and a water supply conduit leading into, and through which water is supplied to said water chamber.
9. In an electrolytic gas generator, a casting having an electrode compartment, and a gas chamber above said compartment; a water chamber located above said compartment; a gas outlet passage leading from said gas chamber into, and discharging below the level of water in said water chamber; a water supply pipe leading from said water chamber and through which water is supplied to said electrode compartment, and having a water seal for preventing the flow of gas 70

a water supply conduit leading into said water chamber below the level of water therein and through which water is supplied to said water chamber.

- 5 13. In an electrolytic gas generator having an internal compartment adapted to contain a liquid, and a gas outlet conduit leading therefrom; a liquid sealing device included in said gas outlet conduit; a liquid supply 70 passage leading from said sealing device and through which liquid is supplied to said internal compartment; and a water supply conduit leading into, and through which water is supplied to said liquid sealing device, the inlet end of said conduit being in 75 permanently open communication with the atmosphere and extending above the level of liquid in said liquid sealing device a distance such that the column of water in said 80 conduit will prevent the outflow of gas therethrough from said liquid sealing device.
14. In an electrolytic gas generator having an internal compartment adapted to contain a liquid; a water chamber located 85 above said compartment; a gas outlet passage leading from said compartment, and the discharge end of which is sealed by the water in said water chamber; a gas outlet conduit leading from said water chamber; a 90 water supply passage leading from said water chamber and through which water is supplied to said internal compartment; and a water supply conduit leading into, and through which water is supplied to said 95 water chamber, the inlet end of said conduit being in permanently open communication with the atmosphere and extending above the level of water in said water chamber a distance such that the column of water in 100 said conduit will prevent the outflow of gas therethrough from said water chamber.
15. In an electrolytic gas generator having an electrode compartment, and a gas chamber above said compartment; a water 105 chamber located above said compartment; a gas outlet passage leading from said gas chamber into, and having a water seal within said water chamber; a water supply pipe leading from said water chamber and 110 through which water is supplied to said electrode compartment, said pipe having a water seal at its lower end for preventing the flow of gas therethrough; a gas outlet conduit leading from said water chamber; and a water supply conduit leading into, and through which water is supplied to said 115 water chamber, the inlet end of said conduit being in permanently open communication with the atmosphere and extending above the level of water in said water chamber a distance such that the column of water in said conduit will prevent the outflow of gas therethrough from said water chamber.
16. In an electrolytic gas generator, a 120 casing having an electrode compartment, and a gas chamber located above said compartment; a gas outlet pipe leading from said gas chamber into said water chamber and having a bell open at its bottom and the lower end of which is submerged in the water in said water chamber; a water supply pipe located within said gas outlet pipe and the upper end of which communicates with the interior of said water chamber 125 above the normal level of water therein and through which pipe water is supplied to said electrode compartment, said water supply pipe having a water seal for preventing the flow of gas therethrough; a gas outlet conduit leading from said water chamber; and a water supply conduit leading into, and through which water is supplied to said water chamber.
17. In an electrolytic gas generator, a casing having an electrode compartment, and a gas chamber above said compartment; a water chamber located above said compartment; a gas outlet pipe leading from said gas chamber into said water chamber and 130 having a bell open at its bottom and the lower end of which is submerged in the water in said water chamber; a water supply pipe located within said gas outlet pipe and the upper end of which communicates with the interior of said water chamber above the normal level of water therein and through which pipe water may flow into said electrode compartment, said water supply pipe having a water seal for preventing the flow of gas therethrough; a gas outlet conduit leading from said water chamber; and a water supply conduit leading into said water chamber and discharging below the level of water therein, the inlet end of said conduit being in permanently open communication with the atmosphere and extending above the level of water in said water chamber a distance such that the column of water in said conduit will prevent the outflow of gas therethrough from said water chamber.
18. In an electrolytic gas generator having electrode compartments within which gases of two kinds are produced; two water chambers; two gas outlet passages through which the gases produced are conducted from said casing, which passages discharge into, and are sealed by the water in said water chambers; two gas outlet passages leading one from each of said water chambers; two water supply conduits leading one into each of said water chambers, and which conduits extend to a height such that the columns of water in them will prevent the outflow of gas from said water chambers through said conduits; and a water supply receptacle in permanently open communication with the atmosphere and with which the inlet ends of all of said water supply conduits are connected.

19. In an electrolytic gas generator, a casing having electrode compartments within which gases of two kinds are produced; two water chambers located above said casing; two gas outlet passages through which the gases produced are conducted from said casing, which passages lead one into each of said water chambers and are provided each with a water seal; two gas outlet passages leading one from each of said water chambers; two water supply pipes leading one from each of said water chambers and through which water is supplied to said electrode compartments, which pipes have each a water seal to prevent the flow of gas therethrough; two water supply conduits leading one into each of said water chambers, and which conduits extend to a height such that the columns of water in them will prevent the outflow of gas from said water chambers through said conduits; and a water supply receptacle in permanently open communication with the atmosphere and with which the inlet ends of all of said water supply conduits are connected. 70
20. In an electrolytic gas generator, a casing having a plurality of electrode compartments, and a plurality of gas chambers located one above each electrode compartment; two water chambers located above said casing; two gas outlet passages through which gases of two kinds are conducted from said gas chambers, which passages discharge one into each of said water chambers and are provided each with a water seal within the chamber into which it leads; two gas outlet conduits leading one from each of said water chambers; two water supply pipes leading one from each of said water chambers and through which water is supplied to said electrode compartments, which pipes are provided each with a water seal to prevent the flow of gas therethrough; two water supply conduits leading one into each of said water chambers, and which conduits extend to a height such that the columns of water in them will prevent the outflow of gas from said water chambers through said conduits; and a water supply receptacle in permanently open communication with the atmosphere and with which the inlet ends of all of said supply conduits are connected. 75
21. In an electrolytic gas generator having a plurality of internal liquid containing compartments, and a plurality of gas chambers located one above each liquid compartment; a plurality of water supply conduits, one discharging into each of said liquid compartments, the upper ends of said conduits being open to the atmosphere and the lower ends thereof terminating below the level of liquid in said compartments; and means whereby liquid may be supplied to all of said conduits simultaneously. 80
22. In an electrolytic gas generator hav-
- ing a plurality of internal liquid containing compartments; a plurality of liquid supply conduits, one of said conduits discharging into each of said internal compartments; and means whereby more liquid is caused to flow through some of said conduits than through others. 85
23. In an electrolytic gas generator having a plurality of electrode compartments; a plurality of water supply conduits, one of said conduits discharging into each of said electrode compartments; means whereby water may be supplied to all of said conduits simultaneously; and means whereby more water is caused to flow through some of said conduits than through others. 90
24. In an electrolytic gas generator having a plurality of electrode compartments; means for supplying water to all of said compartments simultaneously; and means associated with said water supplying means whereby more water is supplied to some of said compartments than to others of them. 95
25. In an electrolytic gas generator having a plurality of electrode compartments; a water receiving receptacle; and a plurality of water supply conduits, one discharging into each of said electrode compartments, and the inlet ends of which conduits open into said receptacle at different levels. 100
26. In an electrolytic gas generator having a plurality of electrode compartments; means for supplying water to all of said compartments simultaneously; and means associated with said water supplying means whereby more water is supplied to the cathode compartments than to the anode compartments. 105
27. In an electrolytic gas generator having a plurality of electrode compartments; a water receiving receptacle; a conduit leading from said receptacle and discharging into an anode compartment; and a second conduit leading from said receptacle at a lower level than the inlet end of said first mentioned conduit and discharging into a cathode compartment. 110
28. In an electrolytic gas generator having two anode compartments, and a cathode compartment located between said anode compartments; a water receiving receptacle; two water supply conduits the inlet ends of which communicate with said receptacle at substantially the same level, and which conduits lead into the anode compartments aforesaid; and a third water supply conduit the inlet end of which communicates with said receptacle at a lower level than the level of the inlet ends of said first mentioned conduits, and which conduit leads into the cathode compartment. 115
29. In an electrolytic gas generator, a closed receptacle or casing comprising two end section members, together with one or more intermediate annular or ring-like sec- 120
- 125
- 130

- tion members, all of which are secured together; electrodes located within said casing; filling means for said casing; and means for conducting the gases produced 5 from the interior of said casing.
30. In an electrolytic gas generator, a closed receptacle or casing comprising two dished end section members, together with one or more intermediate annular or ring-like section members, all of which are secured together; means for dividing the interior of said casing into a plurality of electrode compartments; a plurality of electrodes located one within each of said electrode 10 compartments; filling means for said casing; and means for conducting the gases produced from said electrode compartments.
31. In an electrolytic gas generator, a closed receptacle or casing comprising two end section members, together with one or more intermediate annular or ring-like section members, all of which are secured together; a plurality of partitions arranged within the upper portion of said casing; a plurality of 15 porous diaphragms located one beneath each of said partitions; a plurality of electrodes located within said casing and arranged in alternation with said diaphragms; filling means for the casing; and means for conducting the gases produced 20 from said gas chambers.
32. In an electrolytic gas generator, a closed receptacle or casing comprising two end section members, together with one or more intermediate annular or ring-like section members, all of which are secured together; a plurality of frame members arranged in alternation with and held in place 25 between the ends of adjacent section members; a plurality of porous diaphragms carried one by each of said frame members; electrodes located within said casing and arranged in alternation with said diaphragms; filling means for said casing; and means for 30 conducting the gases produced from the interior of said casing.
33. In an electrolytic gas generator, a closed receptacle or casing comprising two dished end section members, together with one or more intermediate annular or ring-like section members, all of which are secured together; a plurality of frame members arranged in alternation with said section members and which frame members are 35 held in place between the edges of adjacent section members, and the upper ends of which frame members form partitions whereby the interior of said casing is divided to form a plurality of gas chambers; a plurality of diaphragms carried one by each of said frame members and extending downward from said partitions; a plurality of electrodes located one beneath each of said 40 gas chambers; filling means for said casing; and means for conducting the gases produced from the interior of said casing.
34. In an electrolytic gas generator, a closed receptacle or casing made up of a plurality of parts or sections secured together, the end sections of said casing comprising dished casing members and the intermediate sections comprising a plurality of annular or ring-like sections; a plurality of partitions arranged in alternation with said casing parts or sections, so that a partition 45 is located between each two successive sections of the casing, and which partitions divide the interior of the casing into a plurality of gas chambers; diaphragms located within the casing and arranged one below each of said partitions; a plurality of electrodes located within the casing and arranged upon opposite sides of said diaphragms; filling means for the casing; and means for conducting the gases produced 50 from said gas chambers.
35. In an electrolytic gas generator, a closed receptacle or casing made up of a plurality of parts or sections secured together, the end sections of said casing comprising dished casing members and the intermediate sections comprising a plurality of annular or ring-like sections; a plurality of partitions arranged in alternation with said casing parts or sections, so that a partition 55 is located between each two successive sections of the casing, and which partitions divide the interior of the casing to thereby provide a plurality of gas chambers; a plurality of electrodes located within the casing and arranged one beneath each of said gas chambers; a plurality of porous diaphragms located beneath said partitions and arranged in alternation with said electrodes; filling means for the casing; and means for conducting the gases produced 60 from said gas chambers.
36. In an electrolytic gas generator, a closed receptacle or casing made up of a plurality of parts or sections secured together, the end sections of said casing comprising dished casing members having each a flange at its free edge, and the intermediate sections comprising a plurality of annular or ring sections each having a flange 65 at each of its ends; a plurality of frame members arranged in alternation with said casing parts or sections, so that a frame member is located between each two successive parts or sections of the casing, and which frame members extend and are held in place between the flanges of adjacent parts or sections of the casing and divide the interior thereof into a plurality of compartments; a plurality of porous diaphragms carried one by each of said frame members; a plurality of electrodes located one within 70 each of said compartments; filling means for 75

- supplying liquid to said several compartments; and conduits leading from said compartments and through which gas may pass therefrom.
- 5 37. In an electrolytic gas generator, a closed receptacle or casing comprising two dished end section members, together with an intermediate annular or ring-like section member, all of which are secured together; 10 two frame members held in place between the ends of adjacent section members; two porous diaphragms, one carried by each of said frame members, whereby the interior of said casing is divided into three electrode compartments; two anodes located one within each of the outer of said electrode compartments; a cathode located within the middle of said electrode compartments; filling means for said casing; and means for 15 conducting the gases produced from said electrode compartments.
38. In an electrolytic gas generator, a closed receptacle or casing comprising two dished end section members, together with 20 an intermediate annular or ring-like section member, all of which are secured together; two frame members held in place between the ends of adjacent casing members and the upper portions of which form partitions 25 which divide the upper portion of said casing into three gas chambers; two porous diaphragms carried one by each of said frame members, whereby the lower portion of said casing is divided into three electrode compartments; two anodes located one within 30 each of the outer of said electrode compartments; a cathode located within the middle of said electrode compartments; filling means for said casing; and means for conducting 35 the gases produced from said gas chambers.
39. In an electrolytic gas generator, a closed receptacle or casing made up of a plurality of section members secured together; a plurality of partitions located within the 40 upper portion of said casing; a plurality of porous diaphragms located beneath and the upper ends of which are secured one to each of said partitions, and the lower ends of which diaphragms terminate above the 45 lower end of said casing; means engaging the side and bottom edges of said diaphragms to thereby hold said edges in fixed positions; electrodes located within said casing; filling means for said casing; and 50 means for conducting the gases produced from the interior of said casing.
40. In an electrolytic gas generator, a closed receptacle or casing; a frame member comprising an upper portion adapted to 55 form a partition for dividing the interior of said casing into a plurality of gas chambers, and two oppositely located side portions depending from said upper portion; a porous diaphragm the top and side edges 60
- of which are secured to the lower edge of 65 said upper portion and to said side portions; and which diaphragm terminates above the lower end of said casing; and means extending between said side portions and connected therewith and with the lower edge of said 70 diaphragm to thereby hold said lower edge in a fixed position.
41. In an electrolytic gas generator, a frame member comprising an upper portion adapted to form a partition, two oppositely located side portions depending from said upper portion, and a bottom member extending between the lower ends of said side portions; a porous diaphragm the top and side edges of which are secured to said upper 80 portion and to said side portions, and which diaphragm terminates above said bottom member; and means for connecting the lower edge of said diaphragms with said bottom member to thereby hold said lower 85 edge in a fixed position.
42. In an electrolytic gas generator, a frame member comprising an upper portion adapted to form a partition, two oppositely located side portions depending from said 90 upper portion, a bottom bar or strip connecting the lower ends of said side portions with one another, and a plurality of lugs extending upward from said bottom bar or strip. 95
43. In an electrolytic gas generator, a frame member comprising an upper portion adapted to form a partition, two oppositely located side portions depending from said upper portion, a bottom bar or strip connecting the lower ends of said side portions with one another and a plurality of lugs extending upward from said bottom bar or strip; together with a porous diaphragm the top and side edges of which are secured 100 to said upper portion and to said side portions, and the lower edge of which is secured to said lugs. 105
44. In an electrolytic gas generator, a closed receptacle or casing; a partition located within said casing and extending from the upper end thereof downward below the level of liquid therein, whereby a gas chamber is provided upon each side of said partition; two electrodes located one below each 110 of said gas chambers; and means for equalizing the level of liquid upon opposite sides of said partition. 115
45. In an electrolytic gas generator, a closed receptacle or casing; a partition located within said casing and extending from the upper end thereof downward below the level of liquid therein, whereby a gas chamber is provided upon each side of said partition; two electrodes located one below each 120 of said gas chambers; and an equalizing passage located adjacent the level at which the liquid stands in said casing, and 125

through which liquid may flow from one side of said partition to the other.

46. In an electrolytic gas generator, a closed receptacle or casing; a partition located within said casing and extending from the upper end thereof downward below the level of liquid therein, whereby a gas chamber is provided upon each side of said partition; two electrodes located one below each of said gas chambers; and a passage located adjacent the level at which the liquid stands in said casing and extending from one side of said partition through the same and to the other side thereof, and through which liquid may flow from one side of said partition to the other.

47. In an electrolytic gas generator, a closed receptacle or casing; a partition located within said casing and extending from the upper end thereof downward below the level of liquid therein, whereby a gas chamber is provided upon each side of said partition; two electrodes located one below each of said gas chambers; and two channel members secured to and located upon opposite sides of said partition, the upper ends of said channels extending above the level of liquid in said casing and being in permanently open communication with the gas chambers into which they extend, and each of which channels is provided with an opening below the level of liquid in said casing; said partition having an opening within said channel members and below the openings aforesaid in said channels.

48. In an electrolytic gas generator, a closed receptacle or casing; a partition located within said casing and extending from the upper end thereof downward below the level of liquid therein, whereby a gas chamber is provided upon each side of said partition; two electrodes located one below each of said gas chambers; and a porous diaphragm extending downward from the lower edge of said partition and between said electrodes.

49. In an electrolytic gas generator, a closed receptacle or casing; a partition located within said casing and extending from the upper end thereof downward below the level of liquid therein, whereby a gas chamber is provided upon each side of said partition; two electrodes located one below each of said gas chambers; and a porous diaphragm extending downward from the lower edge of said partition and terminating above the bottom wall of said casing, whereby openings are provided beneath said diaphragm.

50. In an electrolytic gas generator, a closed receptacle or casing, a partition located within said casing and extending from the upper end thereof downward below the level of liquid therein, whereby a gas cham-

ber is provided upon each side of said partition; and a porous diaphragm located between said electrodes, the upper edge of which is secured to the lower edge of said partition, and the lower edge of which terminates above the bottom wall of said casing.

51. In an electrolytic gas generator, a casing; an electrode located within said casing and having a support adjacent its lower end; a holding member located within said casing and adjacent said support, and to which said support may be secured; means for securing said support to said holding member; and an absorbent insulating material intermediate said holding member and said support.

52. In an electrolytic gas generator, a casing; an electrode located within said casing and having a support adjacent its lower end; a holding member located within said casing and adjacent said support, and to which said support may be secured; means for securing said support to said holding member; and an absorbent insulating material having asbestos as an ingredient whereby said support is insulated from said holding member.

53. In an electrolytic gas generator, a casing; a pocket secured in place within said casing and adjacent the lower end thereof, said pocket having spaced side walls each of which is provided with a hole; an electrode located within said casing and having a support adapted to enter the pocket aforesaid and having a hole; a pin of nonconducting material extending through the holes in the side walls of said pocket and in said support; and insulating material within said pocket and between the walls thereof and said support.

54. In an electrolytic gas generator, a casing substantially rectangular in form; two pockets secured in place within the lower end of said casing and in the corners thereof, said pockets each having spaced side walls and each wall having a hole; an electrode located within said casing and having two supports extending one into each of the pockets aforesaid, and having each a hole; two pins, one associated with each pocket, which pins extend through the holes in the side walls of said pockets and in said supports; and insulating material within each of said pockets and between the walls thereof and said supports.

55. In an electrolytic gas generator having a plurality of compartments generating gas of the same kind, said generator having means whereby the gas from any one compartment may escape into the atmosphere independently of the gas from the other compartments.

56. In an electrolytic gas generator hav-

ing a plurality of compartments generating gas of the same kind, each of said compartments having an independent vent through which the gas within said compartment may escape to the atmosphere independently of the gas from other compartments.

In testimony whereof I have signed my

name to this specification this 20th day of October, 1916.

ISAAC H. LEVIN.
